ASSIGNORS TO WESTINGHOUSE ELECTRIC AND MANUFACTURING COMPANY, A COR-
PORATION OF PENNSYLVANIA

DESK

Application filed March 17, 1927. Serial No. 176,034.

Our invention relates generally to desks, and more particularly to office desks in conjunction with which modern office devices may be conveniently provided.

One object of the invention is to facilitate 5 the wiring of desks to provide the proper conductors and connections for telephones, dictaphones and other devices requiring a supply of electrical energy for their operation.

It is also an object of the invention to provide desks having passage-ways and conduits disposed to register when the desks are assembled in groups, thereby to provide continuous channels through all the desks for 15 containing the conductors for the auxiliary equipment.

Heretofore, it has been necessary to wire desks individually, usually resulting in disfigurement, by reason of the necessity of fastening various terminals and clips on the desk to support the wires in accessible positions.

When a desk embodying our invention is 25 employed, defects in wiring may be easily corrected, conductors may be changed quickly, and the substitution of one wired desk for another is a simple matter.

Our improved desk comprises a desk body 30 having a channel or a plurality of channels located in its upper rear part and extending from end to end thereof and a desk top that rests on and covers the desk body and the channels therein.

For a fuller understanding of the nature 35 and objects of our invention, reference is to be had to the following description taken in conjunction with the accompanying drawing in which;

Fig. 1 is a view, in perspective, of a desk 40 constructed in accordance with one form of our invention, a part of the top or cover being broken away;

Fig. 2 is a top plan view of the channel member with open top shown in the upper 45 part of the desk body of Fig. 1;

Fig. 3 is a bottom plan view of the channel member illustrated in Fig. 2;

Fig. 4 is a longitudinal sectional view of

the cover of the desk taken along the line IV-IV of Fig. 1; and

Fig. 5 is a view, in cross-section, taken along the line V-V of Fig. 2.

In the drawing, we have illustrated a desk 55 comprising a right pedestal 1 and a left pedestal 2 that are connected by a bridge member 3 to provide a desk body adapted to support a removable top or cover 4. A portion of the removable top 4 has been broken 60 away to disclose the arrangement of the different members mounted in the desk body.

A channel member 6 comprising an outer channel body 7 and an inner channel body 8 nested therein and united thereto to form a 65 plurality of open channels, is located in the upper rear part of the desk body. As illustrated the channels contain telephone wires 9 and 10 provided with a take-off 11 which extends through an opening in the bottom of 70 the desk into the knee space provided in the central part under the bridge member 3 and which leads to a telephone set 12.

The channel body 7 constituting the outer 75 part of the channel member 6, is constructed by pressing any suitable sheet material, preferably metal, into the form of a trough or channel and by then bending the outer longitudinal edges 13 and 14 of its side walls 15 and 16 inwardly to form a constricted opening thereto. The ends of the outer channel body 7 are bent outwardly to form flanges 17, 80 that are adapted to rest against the walls of the pedestals 1 and 2 and hold the channel body 6 in position when it is placed in the 85 desk body.

The inner channel body 8, which is adapted to be nested in the outer channel body 7, is also formed by pressing sheet material into the form of a trough with its outer longitudinal edges 18 and 19 bent outwardly. The inner channel body 8 is then placed or nested in the outer channel body 7 in such position that its side walls will divide the interior of the channel body 7 into a plurality of channels and its bent-over longitudinal edges 18 and 19 will cooperate with the inturned edges 13 and 14 of the channel body 7, thereby providing constricted openings into the outer channels and leaving the central channel with 95 100

a full-width opening. The inner channel body 8 may be fastened in the outer channel body 7 by welding or in any other well known manner.

6 The channel member 6 is provided with apertures 20 in its underside near its central portion through which wires or air lines may be led out into the open knee space and up over the back of the desk to telephones, electric light fixtures, dictaphones, or other devices mounted upon or close to the desk. Apertures may be provided in any other portion of the channel member 6, if it is desired to lead out wires at any other point.

15 The desk top 4 or cover and the desk body are provided, at each corner, with co-operating clips 21 and screws 22 by means of which the top 4 may be rigidly fastened to the body. If it is desired to inspect the contents of the 20 channels or conduits formed by the channel bodies 7 and 8 or place new wires therein, the desk top 4 may be readily removed by taking out the screws 22.

25 The edges 23 of the desk top 4 are turned downwardly and inwardly to give a neater appearance to the desk and to conceal the open ends of the channel member 6 from the usual line of vision of the occupants of the room in which the desk may be located.

30 In wiring our improved desk, the wires may be threaded through the channels or conduits in the channel member 6 and connected to telephones, dictaphones or other instruments associated with the desk without 35 removing the desk top, but it may sometimes be more convenient to remove the desk top, lay the wires in the channels and then replace the top.

40 While the desk illustrated in the drawing is shown as having telephone wires located in its channels or conduits, wires for dictaphones, electric lighting fixtures, or for any other purpose may be inserted therein, or some or all of the channels may be used as 45 runways for air pipes for air brushes and the like.

45 It will also be understood that a desk constructed in accordance with our invention may be provided with a larger conduit or channel member for other purposes, such for instance, as enclosing and supporting a traveling belt conveyor, or a cable having individual carriers, for facilitating the handling of papers or small packages.

50 Many modifications and changes may be made in the desk and channel member illustrated as embodying our invention without departing from the spirit and scope thereof, and all such modifications and changes are 55 intended to be covered by the appended claims.

We claim as our invention:

60 1. A desk comprising a body portion and an open-end conduit located therein and ex-

tending from one end to the other end thereof.

2. A desk comprising a body portion and a conduit located therein and extending from one end to the other end thereof, said conduit being provided with an outlet for leading-out conductors. 70

3. A desk comprising a body portion and a conduit located therein and extending from one end to the other end thereof, said conduit being provided with an outlet near its central portion for leading-out conductors. 75

4. A desk for office use comprising a body portion, a removable top portion mounted on the body portion, and a conduit for auxiliary apparatus in the body portion, said conduit being normally concealed by the top portion and freely accessible when the top portion is removed. 80

5. A desk for office use comprising a body portion, a channel member for receiving auxiliary apparatus in the body portion and a top portion disposed to cover the body portion and the channel member therein, said channel member comprising a channel shaped conduit open at its ends and provided with apertures in its bottom portion. 85

6. In a desk for office use, the combination with a pair of spaced pedestal members, a connecting bridge member to constitute a desk body having the usual knee space and a removable top portion; of a channel member for receiving auxiliary apparatus disposed in the upper rear portion of the desk body, said channel member having openings at either end of the desk and an opening communicating with the knee space and being freely accessible by removing the top portion. 90

In testimony whereof, we have hereunto subscribed our names this 10th day of March, 1927.

MALCOLM CARRINGTON.
JOHN HENRY KLINCK.
